SLIDE BUCKLE

Walter W. Hoffland, Glendo, Wyo., assignor to
The Waterbury Buckle Company, Waterbury,
Conn., a corporation of Connecticut

Application April 19, 1940, Serial No. 330,442

12 Claims. (Cl. 24—196)

The present invention relates to improvements in buckles, and more particularly to improvements in slide-buckles of the general type wherein a gripping-member is automatically moved transversely with respect to a frame or body-member to grip a strap or the like when the said gripping-member is moved longitudinally with respect to the said frame or body-member.

One of the main objects of the present invention is to provide a superior buckle of the type referred to and characterized by having its parts so constructed and arranged as not to require the back-and-forth threading of a strap in order to grip the same.

Another object of the present invention is to provide a superior slide-buckle of the character referred to in which the major portion of the buckle may be substantially concealed by the strap-portion which it grips.

A further object of the present invention is to provide a superior slide-buckle of the type referred to and which has its elements so constructed and arranged as to enable a strap to be gripped against the front surface of the frame or body-member rather than against the rear face thereof, so that a relatively-small gripping-member may be substantially all that interrupts the otherwise apparent continuity of such strap.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a perspective view of a belt for personal wear equipped with a slide-buckle embodying the present invention;

Fig. 2 is a fragmentary view thereof in front elevation;

Fig. 3 is a transverse sectional view taken on the line 3—3 of Fig. 2, but on a larger scale;

Fig. 4 is a broken view in central-longitudinal section taken on the line 4—4 of Fig. 2 but on a larger scale;

Fig. 5 is a perspective view of the body-member detached;

Fig. 6 is a perspective view of the gripping-member, detached;

Fig. 7 is a face view of another form of slide-buckle embodying the present invention;

Fig. 8 is a longitudinal sectional view thereof

taken on the line 8—8 of Fig. 7, but on a larger scale;

Fig. 9 is a transverse sectional view taken on the line 9—9 of Fig. 7, but on a larger scale;

Fig. 10 is a perspective view of the slide-buckle shown in Figs. 7 to 9 inclusive.

Fig. 11 is a view in front elevation of still another form of slide-buckle embodying the present invention, and shown in conjunction with parts of both the fixed-end and free-end of a belt;

Fig. 12 is a view thereof in rear elevation;

Fig. 13 is a transverse sectional view taken on the line 13—13 of Fig. 11, but on a larger scale;

Fig. 14 is a view in central-longitudinal section taken on the line 14—14 of Fig. 11, but on a larger scale;

Fig. 15 is an elevational view showing the slide-buckle of Figs. 11 to 14 inclusive reversed face-for-face to cause the face shown in Fig. 12 to become the front face of the slide-buckle.

Fig. 16 is a perspective view of the gripping-member of the buckle-structure shown in Figs. 11 to 15 inclusive; and

Fig. 17 is a perspective view of the main or body-member of the buckle-structure of Figs. 11 to 15 inclusive.

The buckle of Figs. 1 to 6, inclusive

30 The particular embodiment of the present invention shown in the figures referred to, comprises a body-member or frame generally designated by the reference character 20, and a gripping-member 21 slidable lengthwise of the said body-member.

The body-member 20 above referred to, includes a substantially-flat front-panel 22 from the respective opposite side-edges of which rearwardly project longitudinally-extending side-walls 23—23 coupled together at their outer ends by an integral outer end-wall 24. Adjacent its outer end, the front-panel 22 of the body-member 20 is provided with a series of transversely-extending flutes 25 to provide a gripping surface 45 for the retention of a strap, in a manner as will hereinafter appear.

Adjacent its inner end, the body-member 20 is formed with a transversely-extending strap-receiving slot 26 having its outer wall constituted by the inner edge of an integral strap-attaching bar 27. Also adjacent its inner end and hence adjacent both the slot 26 and the bar 27, the body-member 20 has its side walls increased in depth for a short distance to provide rearwardly-projecting stop-ears 28—28 for limiting

the movement of the gripping-member 21, in a manner as will hereinafter appear.

Forwardly of its stop-ear 28, each of the two side-walls 23-23 of the body-member 20 slopes away from the strap-attaching bar 27 and away from the front-panel 22 thereof to provide each of the said side-walls with a rearwardly-facing inclined camming-surface 29 constituting portions of the rear-face of the said body-member 20.

The body-member or frame 20 above referred to may be conveniently stamped up from sheet metal in an economical manner to provide a structure of adequate strength.

The gripping-member 21 before referred to comprises a front gripping-bar 30 extending transversely across the front face of the front-panel 22 of the body-member 20. Formed integral with each of the respective opposite ends of the gripping-member 21 is one of two rearwardly-extending J-shaped side-arms 31-31. Each of the said side-arms 31-31 extends rearwardly along the outer face of the adjacent one of the two side-walls 23-23 of the body-member 20 and is provided with an inturned portion or cam-surface 32 providing a forwardly-facing cam-surface for engagement with the camming-surface 29 of the adjacent one of the side-walls 23-23. Inwardly of its cam-surface 32, each J-shaped in cross-section side-arm 31 is formed with a forwardly-projecting guard-finger 33 extending forwardly adjacent the inner face of the adjacent one of the side-walls 23-23 of the body-member 20, as is especially well shown in Fig. 3.

In use the slide-buckle has the so-called "fixed-end" 34 of a strap such for instance as the belt 35 shown particularly well in Fig. 1, wrapped around its strap-attaching bar 27 and sewn or otherwise secured in place, as is particularly well shown in Fig. 4. The free end 36 of the belt 35 is slipped beneath the gripping-bar 30 of the gripping-member 21 and over the forward face of the front-panel 22 of the body-member 20 and in a direction from the front end-wall 24 toward the strap-attaching bar 27.

During the operation of inserting the free end 36 of the belt 35 beneath the gripping-bar 30 as just above described, the gripping-member 21 will, if not already so positioned, be moved toward the strap-attaching bar 27 to thus provide ample space for the insertions referred to.

After the free end 36 of the belt 35 has been inserted as above described and the gripping-member 21 has been moved outwardly toward the end-wall 24 of the body-member 20, the said free end 36 will be clamped between the gripping-bar 30 and the flutes 45 of the said body-member. This clamping action will be effected by the riding of the cam-surfaces 32-32 of the gripping-member 21 rearwardly and outwardly along the complementary camming-surfaces 29-29 of the body-member 20.

The release of the free end 36 of the strap 35 may be effected by pulling the same in the direction of the arrow A shown in Fig. 4 to thereby cause the gripping-member 21 to ride along the camming-surfaces 29-29 of the body-member 20 in the general direction of the strap-attaching bar 27 to thus retire its gripping-bar 30 further away from the front-panel 22 and into the position indicated by broken lines in Fig. 4. If desired, the release of the free end 36 may be effected by directly grasping the gripping-member 21 and shifting the same into the position indicated by broken lines in Fig. 4.

The gripping-member 21 is prevented from

sliding off from the body-member 20 in the direction of the strap-attaching bar 27 by the coaction of the folded portion of the fixed end 34 of the belt 35 and the stop-ears 28-28 of the body-member 20.

When the free end 36 of the belt 35 is removed from beneath the gripping-bar 30 of the gripping-member 21, the said gripping-member is prevented from sliding off from the outer end of the body-member 20 by the engagement of its guard-fingers 33-33 with the inner face of the end-wall 24 of the said body-member.

The buckle of Figs. 7 to 10, inclusive

In the structure shown in the figures just above referred to, a longitudinally-tapered body-member 37 is employed. The said body-member is formed by reversely bending a sheet of brass or other suitable material to provide a front-panel 38 and a complementary rear-panel 39 both united at their outer ends by an integral semicylindrical outer end-wall 40. From their point of juncture with the outer end-wall 40 the front-panel 38 and the rear-panel 39 converge toward each other in the direction of the inner end of the body-member 37, as is shown particularly well in Figs. 8 and 10. The inner ends of the two said panels 38 and 39 lie in contact and in parallelism with each other to provide a rectangular strap-receiving slot 41 extending crosswise of the body-member 37. The respective inner ends of the front-panel 38 and the rear-panel 39 cooperate to provide a laminated strap-attaching bar 42 around which the fixed end of a suitable strap may be wrapped. The inner end of the front-panel 38 is extended and bent rearwardly and outwardly to provide a coupling-lip 43 engaging with the rear face of the adjacent portion of the rear-panel 39 to hold the inner ends of the two said panels together as is particularly well shown in Figs. 8 and 10.

Adjacent the outer end-wall 40 the front-panel 38 of the body-member 37 is formed with a series of transverse flutes 44 as is particularly well shown in Fig. 8, and against which the free end of a suitable strap may be clamped by a gripping-member 45 which includes a relatively-narrow gripping-bar 46 extending transversely across the front face of the front-panel 38. Extending rearwardly from each of the respective opposite ends of the gripping-bar 46 just referred to is one of two complementary L-shaped side-arms 47-47. Projecting laterally inwardly from the rear end of each of the side-arms 47-47 is one of two cam-fingers 48-48 inclined with respect to the gripping-bar 46 to a degree sufficient to cause the said gripping-bar to extend in substantial parallelism with the front-panel 38 of the body-member 37. Each of the cam-fingers 48-48 thus, under normal conditions, has camming engagement with the adjacent portion of the rear face of the rear-panel 39 to thus cause the gripping of a suitable strap by the gripping-bar 46 when the gripping-member 45 is moved toward the outer end of the body-member 37.

To guard against the detachment of the gripping-member 45 by riding off the outer end of the body-member 37, the outer end-wall 40 of the said body-member is extended transversely on each of the respective opposite sides of the said body-member to respectively provide stop-ears 49-49 respectively engageable by the outer edges of the side-arms 47-47 of the gripping-member 45.

To guard against the demounting of the grip-

ping-member 45 by movement inwardly and over the laminated strap-attaching bar 42, the respective inner ends of the said body-member are projected transversely outwardly to provide stop-ears 50—50 respectively engageable by the inner edges of the side-arms 47—47 of the gripping member 45.

As thus constructed and arranged, the slide-buckle illustrated in Figs. 7 to 10 inclusive has the same fundamental characteristics as the structure illustrated in Figs. 1 to 6 inclusive.

The buckle of Figs. 11 to 17, inclusive

This particular slide-buckle includes a body-member 51 which may be conveniently formed by molding the same from any one of a wide variety of synthetic resins. The said body-member 51 is longitudinally tapered, as shown, and includes two opposite faces respectively designated 52 and 53 either one of which may constitute either the back or front of the structure in a manner as will fully hereinafter appear.

The outer end of the body-member 51 is of semi-cylindrical form as at 54, and the material of the said body-member is projected outwardly on each of the respective opposite sides at the said outer end to provide stop-ears 55—55, for the purpose as will hereinafter appear. Adjacent the outer end of the body-member 51, the face 52 thereof is provided with transverse flutes or serrations 56 to provide a gripping-surface and similarly the opposite face 53 of the said body-member 51 is provided with flutes 57.

The inner relatively-thin end of the body-member 51 is formed with an integral transverse strap-attaching bar 58 forming the outer wall of a transverse rectangular strap-receiving slot 59. Threaded through the slot 59 and folded around the strap-attaching bar 58 is the fixed end 60 of a belt or strap 61.

Slidable longitudinally of the body-member 51 is a tubular clamping-member 62 having two spaced-apart face-bars 63 and 64 extending in substantial parallelism with each other in a direction transversely of the body-member 51, but inclined with respect to each other in a direction lengthwise of the said body-member. The two face-bars 63 and 64 are each connected at their respective opposite ends to the other of the face-bars by wedge-shaped integral side-walls 65—65. For purposes of decoration, the face-bar 63 may, if desired, be provided with a slot 66, as is shown especially well in Fig. 16 and the face-bar 64 with any desired ornamentation, such for instance, as the monogram shown in Fig. 12.

The clamping-member 62 may be made of any suitable material such, for instance, as brass.

As before indicated the slide-buckle now being discussed is reversible face-for-face in a manner as will be now more particularly described.

The free end 67 of the belt or strap 61 may be slipped between the inner face of the face-bar 63 of the clamping-member 62 and the face 52 of the body-member 51, as is indicated in Figs. 11 to 14 inclusive, and clamped in place by a relative longitudinal movement between the body-member 51 and the clamping-member 62 in such direction as will bring the said clamping-member toward the outer or thicker end of the said body-member.

For purposes of description, let it be assumed that the belt or strap 61 has its respective opposite faces differentially colored with respect to each other, thus, for instance, the face of the said belt against which the face-bar 63 of the clamp-

ing-member 62 is engaged might, for instance, be black. The opposite face of the strap might, for instance, be brown. Under these circumstances, if it is desired to have the outer face of the said belt or strap 61 show brown coloration, the said strap and the slide-buckle structure may all be reversed into the positions in which they are shown in Fig. 15, and the free end 67 of the said strap threaded inwardly toward the fixed end 60 between the face 53 of the body-member 51 and the opposite face-bar 64 of the clamping-member 62. This reversal is also indicated by broken lines in Fig. 14.

Résumé

15 All of the three forms of the present invention shown in the accompanying drawings and above described, are characterized by simplicity, reliability of action and relative unobtrusiveness of the buckle structure itself.

20 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

25 I claim:

30 1. A slide-buckle including in combination: a body-member having a front face for gripping engagement with the free end of a strap, the said body-member also having rearwardly-facing camming-means inclined with respect to the front face thereof in a direction lengthwise of the body-member; and a gripping-member having a gripping-bar extending transversely across the front face of the said body-member in forwardly-spaced relationship thereto to provide a strap-passage between its rear face and the opposed front face of the said body-member, the said gripping-member also including rearwardly-projecting camming-means engaging with the rearwardly-facing camming-means of the said body-member to effect the rearward movement of the gripping-bar of the gripping-member with respect to the front face of the body-member to clamp a strap against the latter as the said gripping-member is moved longitudinally of the said body-member.

35 2. A slide-buckle including in combination: a body-member having a front face for gripping engagement with the free end of a strap, the said body-member also having rearwardly-facing camming-means inclined with respect to the front face thereof in a direction lengthwise of the body-member; and a gripping-member having a gripping-bar extending transversely across the front face of the said body-member in forwardly-spaced relationship thereto to provide a strap-passage between its rear face and the opposed front face of the said body-member, the said gripping-member also including two rearwardly-projecting portions, one of which extends 40 rearwardly from each of the respective opposite ends of the gripping-bar for engagement with the rearwardly-facing camming-means of the said body-member to effect the rearward movement of the gripping-bar of the said gripping-member with respect to the front face of the said body-member to clamp a strap against the latter as the said gripping-member is moved longitudinally of the said body-member.

45 3. A slide-buckle including in combination: a

body-member having a front face for gripping engagement with the free end of a strap, the said body-member also having two rearwardly-facing camming-surfaces, one of which is located adjacent each side of the said body-member and which is inclined with respect to the front face thereof in a direction lengthwise of the body-member; and a gripping-member having a gripping-bar extending transversely across the front face of the said body-member in forwardly-spaced relationship thereto to provide a strap-passage between its rear face and the opposed front face of the said body-member, the said gripping-member also including two rearwardly-projecting arms one of which extends rearwardly from each of the respective opposite ends of the gripping-bar of the said gripping-member and into engagement with the adjacent one of the two rearwardly-facing inclined camming-surfaces of the said body-member to effect the rearward movement of the gripping-bar of the said gripping-member with respect to the front face of the body-member to clamp a strap against the latter as the said gripping-member is moved longitudinally of the said body-member.

4. A slide-buckle including in combination: a body-member having a front face for gripping engagement with the free end of a strap, the said body-member also having two rearwardly-facing camming-surfaces, one of which is located adjacent each side of the said body-member and which is inclined with respect to the front face thereof in a direction lengthwise of the body-member; and a gripping-member having a gripping-bar extending transversely across the front face of the said body-member in forwardly-spaced relationship thereto to provide a strap-passage between its rear face and the opposed front face of the said body-member, the said gripping-member also including two rearwardly-projecting arms one of which extends rearwardly from each end of the said gripping-bar and along the side edge of the said body-member, each of the two said rearwardly-projecting arms of the gripping-member being formed at its rear with an inwardly-projecting portion providing a forwardly-facing cammingportion engaging with the adjacent one of the two rearwardly-facing camming-surfaces of the said body-member to effect the rearward movement of the gripping-bar of the gripping-member with respect to the front face of the body-member to clamp a strap against the latter as the said gripping-member is moved longitudinally of the said body-member.

5. A slide-buckle including in combination: a longitudinally-tapered body-member having a front face and a rear face provided adjacent each of its respective opposite side edges with one of two camming-surfaces inclined lengthwise of the body-member with respect to the front face thereof; and a gripping-member having a gripping-bar extending transversely across the front face of the said longitudinally-tapered body-member in forwardly-spaced relationship thereto to provide a strap-passage between its rear face and the front face of the said body-member, the said gripping-member having camming-means at each of its respective opposite ends extending into camming-engagement with the adjacent one of the two camming-surfaces of the said body-member to effect the rearward movement of the gripping-bar of the gripping-member with respect to the front face of the

said body-member to clamp a strap as the said gripping-member is moved longitudinally of the said body-member toward the thicker end thereof.

6. A slide-buckle including in combination: a longitudinally-tapered body-member comprising a front-panel and two longitudinally-tapered side-flanges respectively projecting rearwardly from the respective opposite side edges of the 10 said front-panel, the rear edge of each of the said side-flanges providing a rearwardly-facing camming-surface inclined longitudinally of the body-member with respect to the front face of the front-panel thereof; and a gripping-member 15 having a gripping-bar extending transversely across the front face of the front-panel of the said body-member in forwardly-spaced relationship thereto to provide a strap-passage between its rear face and the opposed front face of the 20 front-panel of the said body-member, the said gripping-member also including two rearwardly-projecting arms one of which extends rearwardly from each of the respective opposite ends of the gripping-bar of the said gripping-member and 25 into engagement with the rearwardly-facing longitudinally-inclined edge of the adjacent one of the two side-flanges of the said body-member to effect the rearward movement of the gripping-bar of the said gripping-member with respect to the front face of the front-panel of the body-member to clamp a strap against the latter as the said gripping-member is moved longitudinally of the said body-member.

7. A slide-buckle including in combination: a 30 longitudinally-tapered body-member comprising a front-panel and two longitudinally-tapered side-flanges respectively projecting rearwardly from the respective opposite side edges of the said front-panel, the rear edge of each of the said side-flanges providing a rearwardly-facing camming-surface inclined longitudinally of the body-member with respect to the front face of the front-panel thereof; and a gripping-member 35 having a gripping-bar extending transversely across the front face of the front-panel of the said body-member in forwardly-spaced relationship thereto to provide a strap-passage between its rear face and the opposed front face of the front-panel of the said body-member, the said gripping-member also including two rearwardly-projecting arms one of which extends rearwardly from each of the respective opposite ends of the gripping-bar of the said gripping-member, 40 the rear ends of each of the two said arms of the gripping-member being bent inwardly and then forwardly to respectively provide a portion for camming-engagement with the adjacent longitudinally-inclined edge of one of the side-flanges of the said body-member and to provide a guard-finger extending forwardly adjacent the inner face of the side-flange just referred to.

8. A slide-buckle including in combination: a 45 body-member having a front face for gripping engagement with the free end of a strap, the said body-member also having rearwardly-facing camming-means inclined with respect to the front face thereof in a direction lengthwise of the body-member; and a tubular gripping-member comprising a front bar extending transversely across the front face of the said body-member, a rear bar extending transversely across the rear face of the said body-member for engagement with the camming-means of the latter, and 50 two side arms respectively connecting the op-

posite ends of the said front bar and the said rear bar.

9. A slide-buckle including in combination: a body-member formed of sheet material reversely bent upon itself to provide a front-panel and a back-panel integrally united at their respective outer ends by an outer end-wall and converging toward their opposite ends to provide a longitudinally-tapered structure; and a gripping-member having a gripping-bar extending transversely across the front face of the front-panel of the said body-member, the said gripping-member also including rearwardly-projecting camming-means engaging with the back-panel of the said body-member to effect the rearward movement of the gripping-bar of the said gripping-member as the latter is moved longitudinally with respect to the said body-member.

10. A slide-buckle including in combination: a body-member formed of sheet material reversely bent upon itself to provide a front-panel and a back-panel integrally united at their respective outer ends by an outer end-wall and converging toward their opposite ends to provide a longitudinally-tapered structure; and a gripping-member having a gripping-bar extending transversely across the front face of the front-panel of the said body-member and provided at each of its respective opposite ends with one of two substantially-L-shaped arms each extending rearwardly from the said gripping-bar and thence inwardly into camming-engagement with the back-panel of the said body-member.

11. A reversible slide-buckle including in combination: a longitudinally-tapered body-member having two opposite strap engaging faces slop-

ing with respect to each other longitudinally of the body-member; strap-attaching means at the thinner of the two ends of the said longitudinally-tapered body-member and designed and adapted to have attached thereto the fixed end of a strap; and a gripping-member having two gripping-bars one of which extends transversely across each of the respective opposite faces of the longitudinally-tapered body-member in position to clamp the free end of a strap against the adjacent face of the said body-member as the said gripping-member is moved longitudinally of the said body-member.

12. A reversible slide-buckle including in combination: a longitudinally-tapered body-member having two opposite strap-engaging faces sloping with respect to each other longitudinally of the body-member; strap-attaching means at the thinner of the two ends of the said longitudinally-tapered body-member and designed and adapted to have attached thereto the fixed end of a strap; and a gripping-member having two gripping-bars one of which extends transversely across each of the respective opposite faces of the longitudinally-tapered body-member in position to clamp the free end of a strap against the adjacent face of the said body-member as the said gripping-member is moved longitudinally of the said body-member, each of the two gripping-bars of the said gripping-member being sloped with respect to each other in a direction longitudinally of the said body-member to substantially conform in slope to the respective slopes of the two opposite faces of the said tapered body-member.

WALTER W. HOFFLAND.
